UNITED STATES PATENT OFFICE.

BETHUEL M. DAVIS, OF CHICAGO, ILLINOIS.

DESIGN FOR A MEASURE FOR AUTOMATIC VENDING-MACHINES.

SPECIFICATION forming part of Design No. 35,377, dated December 3, 1901.

Application filed October 26, 1901. Serial No. 80,151. Term of patent 3½ years.

To all whom it may concern:

Be it known that I, BETHUEL M. DAVIS, a citizen of the United States, residing at Chicago, in the county of Cook and State of Illinois, have invented and produced a new and original Design for a Measure for Automatic Vending-Machines, of which the following, in connection with the accompanying drawings, is a full, clear, and exact specification.

In the said drawings, Figure 1 is a plan view of a measure for an automatic vending-machine embodying my design. Fig. 2 is longitudinal sectional view thereof, taken on the line 2 2, Fig. 1; and Fig. 3 is an end elevation looking from the right-hand end.

The leading features of my design consist of a measure for automatic vending-machines having the opening A appearing therein when viewed from the top or bottom, the flat projection B extending from one side of said opening at the top of the article, and the arms C extending from the other side of the article in the opposite direction from the flat projection B.

The opening A, as appears from above or below, is of oblong formation and is apparently constituted by four straight walls D, E, F, G, and from the upper edge of the wall D projects horizontally the flat extension B, which is as wide as the opening A is long.

On the under side and at each edge of the extension B is a downwardly-extending flange H, and at a point intermediate of these flanges and adjacent to the wall D is a boss I.

On the opposite side of the opening A and projecting from the wall F, apparently as a part thereof, are the two arms C, which are in a slightly-lower plane than the extension B and are arranged closer together than the end walls E G.

Projecting from the side wall F at a point midway between the arm C is an inclined extension J, which extends outwardly and downwardly from the wall F, and on each of the arms C, at the outer end thereof and on the inner side, is a hook-like projection or lug K, located outwardly a short distance from a wider and slightly-longer lug or projection L, projecting from each of the arms C, a clear space being between the projections K L on one arm and those on the other.

The lugs or hook-like projections K are beveled at their upper inner corners, as shown at k, and the projections L are rounded or beveled at their upper outer corners, as shown at l.

Having thus described my invention, what I claim as new therein, and desire to secure by Letters Patent, is—

The design for a measure for automatic vending-machines, substantially as herein shown and described.

BETHUEL M. DAVIS.
